UNITED STATES PATENT OFFICE.

WILLIAM A. FRENCH, OF MINNEAPOLIS, MINNESOTA, ASSIGNOR, BY MESNE ASSIGNMENTS, TO NEW JERSEY PATENT COMPANY, OF WEST ORANGE, NEW JERSEY, A CORPORATION OF NEW JERSEY.

DESIGN FOR A MUSIC-CABINET.

50,970.

Specification for Design.

Patented June 26, 1917.

Application filed January 29, 1917. Serial No. 145,331. Term of patent 14 years.

To all whom it may concern:

Be it known that I, WILLIAM A. FRENCH, a citizen of the United States, residing at Minneapolis, in the county of Hennepin and State of Minnesota, have invented a new, original, and ornamental Design for a Music-Cabinet, of which the following is a specification, reference being had to the accompanying drawings, forming part thereof.

Figure 1 is a perspective view of a music

cabinet embodying and illustrating my novel design. Fig. 2 is a plan view of the same.

I claim:

The ornamental design for a music cabinet, as shown.

WILLIAM A. FRENCH.

Witnesses:

CHAS. G. FRENCH,
A. L. SPALDING.
